G. W. WALLACE

PROCESS OF DISTILLING AND GASIFYING SOLID CARBONACEOUS FUEL

Filed Jan. 13, 1926

Inventor.

GEORGE W. WALLACE,

By W. P. McElroy,
Attorney

UNITED STATES PATENT OFFICE.

GEORGE W. WALLACE, OF SAN FRANCISCO, CALIFORNIA.

PROCESS OF DISTILLING AND GASIFYING SOLID CARBONACEOUS FUEL.

Application filed January 13, 1926. Serial No. 81,119.

This invention relates to distilling and gasifying fuel; and it comprises a method of completely utilizing coal, peat, lignites, woods, oil shales and other solid fuels containing volatile matter by distilling to obtain the products of low temperature carbonization and then gasifying the residue to make producer gas, the carbonization and the main gas production being spatially separated but consecutive operations, carbonization being effected in a relatively stationary zone established and maintained at an intermediate point in a relatively short, pervious, moving body or column of fuel with one end (the feed end) relatively cold and the other end (the delivery end) relatively hot, the desired temperature conditions within the column being maintained with the aid of hot producer gas coming from the gasification operation and being stabilized by supplying enough air to form a flame impinging on and heating the delivery end and establishing gas producer conditions in the mass of fuel delivered therebeyond, the flame gases and the gaseous and vaporous products of distillation formed in carbonization being taken forward in the column against the line of movement of the solid materials therein and gasification of the hot material delivered from said face being effected by a draft current containing air, this draft current usually also containing products of combustion or steam, or both; the gases produced in carbonization and in gasification being if desired separately collected either completely or partially; all as more fully hereinafter set forth and as claimed.

The distillation and the gasification of coal are old arts but it has heretofore proved difficult to combine low temperature carbonization or distillation of coal with efficient gasification. Low temperature carbonization is desirable as giving the best yield of the best grade byproducts; oils, tars and gases. Both updraft producers and down-draft producers fail to accomplish this combination. With an updraft producer tars and other liquid products of carbonization condense and trickle down towards the heat to undergo secondary decomposition. As an incident to this it is extremely difficult to keep the fire-bed open in an updraft producer without resort to poking. In the downdraft producer, gases and vapors are

taken away from the hot zone but there are insuperable difficulties in running such a producer continuously; these difficulties arising partly in the feed of fuel and partly from the accumulation of ash.

It is the purpose of the present invention to provide a simple and economical method whereby coal may be distilled to obtain the products of low temperature carbonization and the hot carbonized material be gasified by a draft current while still hot; the two actions being consecutive and taking place in the same apparatus but being spatially separated so that each can be conducted under the best conditions and be independently controlled. In most types of producers all the gas produced in the gasifying zone necessarily passes through preheating zones; making temperature conditions in the latter uncontrollable, and particularly where carbonization occurs. This is not necessary in the present invention, means being provided whereby, some, much, or most of the producer gas can be by-passed. Except with fuels quite poor in fixed carbon, such as some oil shales, there is an excess of producer gas to be by-passed.

While the producer gas formed in the usual operation is at an average temperature and is in sufficient volume to afford all the heat necessary in carbonization, yet the temperature fluctuates and the volume is generally or usually greater than is needed. The carbonization operation cannot be individually controlled and performed under the best conditions; that is under conditions affording the best yield of the best products. Nor can the quite dissimilar fixed gases formed in the two operations be separately collected.

It is the object of the present invention to obviate these disadvantages while retaining the advantages of updraft gas production; and to this end I do most of my gasification on carbonized fuel in a chamber other than that in which carbonization takes place, effecting merely enough gasification in the carbonization chamber to stabilize heating conditions therein.

In the present invention, I establish and maintain a relatively short moving, pervious column of the material to be distilled with one end, the feed end, relatively cool (often not above 212° F.) and the other end, the discharge end, at a very high tem-

perature. In the material at the discharge end is introduced a current of hot producer gas coming from the gasification step. While the average temperature of this gas is sufficient and a sufficient volume can be passed through the fuel, to maintain the temperature gradients I desire within said column, in practice I find it better not to rely wholly upon this source of heat and 10 to supplement it by flame heat. This has the advantage of stabilizing temperature conditions within the carbonizing chamber and making it independent of gasifier conditions and the further advantage of 15 discharging carbonized materials into the producer at a very high temperature, usually around 2000°; which much facilitates the producer operation. To form the flame I supply some air to the producer gas just 20 before it enters the carbonizing chamber, forming a flame impinging on the delivery end. This forms H_2O and CO_2 from H_2 and CO in the gas with development of 25 high temperature locally. The amount of air being relatively small, the flame is of reducing nature; i. e., not all the producer gas entering the carbonizing chamber is burnt. Just beyond the face however, the CO_2 and H_2O are again reduced to CO and 30 H_2 by the carbon with a drop in temperature; the temperature coming back to a normal producer gas temperature, say 1500-1600° F. The increase in temperature caused by the air addition and flame formation is temporary only; but the addition 35 subserves the two purposes of superheating the discharged material and producing a fixed temperature in the column which is independent of producer conditions. While 40 the particular temperature developed at this point in the column may vary somewhat with conditions (volume of air, composition of gas, speed of feed, etc.) in any given operation the temperature developed 45 is constant enough to permit ready establishment and maintenance of a practically stationary, uniformly operating carbonizing zone within the column. The hot gases 50 passing forward meet and heat the materials and are cooled thereby, establishing the desired temperature gradient with a carbonizing zone at a point intermediate the two ends.

With most organic materials decompositon or carbonization is an exothermic action. Once the materials are brought to the reaction temperature, say about 800° F., charring sets in with development of heat. The exact temperature reached depends upon 55 the materials and upon the consumption of heat in radiation, in heating up accompanying mineral matters, etc. Sometimes this exothermic action is masked by heat losses. Sometimes, however, it is sufficient to keep 60 the carbonization going. The amount of hot

gas and of air which are delivered to and pass through the column of carbonizing fuel vary correspondingly. The more exothermic the carbonizing action the less the necessity for heat from this source. 70

In operating on a short moving column (usually horizontal) this exothermic decomposition is utilized to help produce a short mid zone where carbonization can take place under the best conditions. In establishing and maintaining this zone I balance against each other heat conditions at the two ends of the column. At the entry end for the solid material the temperature is relatively low; being that of the incoming materials; or not much above. Generally I do not use preheated materials. Sometimes however as in treating dried peat, the materials may enter rather warm. Often the temperature remains below but approaches 212° F. because of condensation of moisture. Tarry matter and oils boiling at temperatures above 212° F. are also here condensed as far as the volume of gases will permit. At the other end the temperature is that of hot flame gases say 1800-2800° F.; this temperature however dropping at once as the gases pass into the carbonized material, by reason of endothermic producer gas reactions; reduction of CO_2 and H_2O . Somewhere intermediate the two ends a zone of carbonization is instituted and maintained and with a fixed feed of material the zone remains practically stationary, moving but little to either side. The gases and vapors produced in carbonization pass through the incoming material heating it up and drying it and some vapors are themselves condensed to a large extent. However because of the dilution by the flame gases, ordinarily a considerable amount of valuable oily products goes on beyond and must be recovered by cooling and scrubbing the effluent gas. The scrubbed gas is rich from a B. t. u. standpoint and contains hydrocarbons and also some producer gas; that used as a draft current and that produced by the action of the air. 100

The hot materials passing beyond the action of the flame are in condition and at a temperature to undergo ready gasification with the production of producer gas by the action of a suitable draft current. Such a draft current is passed through an accumulating column of materials coming from the carbonizing zone with the production of the usual types of producer gas, viz, mixtures of CO and N_2 with more or less CO_2 and H_2 . The amount of gas obtained of course varies with the materials treated. With bituminous coal containing but little ash, large volumes of gas are obtained in both the carbonizing zone and the producer zone while on the other hand with some oil shales the carbonized material delivered to the pro- 115 120 125 130

ducer may carry only 2 or 3 per cent of fixed carbon, and give a correspondingly low yield of gas in the producer section. Ordinarily however there is an excess of gas over and above that required in the carbonizing zone and this excess may be diverted and collected to be mixed with gas coming from the scrubbers or to be separately used as circumstances may dictate. The two types of gas may be mixed to give mixture of various B. t. u. values. Sometimes, albeit rarely, a portion of the hot producer may be supplied to the carbonizing zone without air addition or production of flame, effecting carbonization by its sensible heat. This however usually means hot gasification in the producer section and I prefer a cooler gasification, partly because this avoids the clinker troubles incident to gasifying most coals at high temperatures and partly because more gas is produced with temperatures restrained by the presence of endothermics. And in any event conditions in the carbonizing column are more easily and accurately controlled when flame heating is used.

In my usual practice with most fuels, the operation is continuous and a single piece of apparatus is used; but the two actions are separated in point of space.

In the present invention granular materials are supplied to a reacting chamber having the form of a short conduit as successive small charges or by a continuous feeding device thereby establishing and maintaining a moving pervious column with the feed end, as stated, often not above 212° F. Through this moving column are passed hot burning gases in countercurrent with production of hot discharged material and of a short zone wherein normal producer actions (reduction of CO_2 and H_2O) occur and a normal producer gas temperature is reestablished. As the materials move forward against the hot gases they become dried and preheated and at some rather definite temperature, say around 800° F. carbonization sets in with a comparatively sudden evolution of gases and vapors. These gases and vapors are carried backward through the cooler material by the heating gases. The moving material quickly carbonizes and passes forward toward the discharge end. In practice, while the zone of carbonization, which is relatively short, may shift backwards and forwards a little, it remains practically stationary. When the carbonized material reaches the zone of higher temperature towards the discharge end it becomes sufficiently heated to reduce the CO_2 and H_2O in the flame gases to CO and H_2 . With the feed end cool, or relatively so, there is a sharp decline in the temperature gradient from the carbonizing zone toward it; or, in other words there is quick cooling of the produced vapors and liquid with avoidance of injurious changes.

The oils and tars suffer from any prolonged action of heat even at the temperature at which they are produced.

In the accompanying illustration I have shown, more or less diagrammatically, certain apparatus useful in the performance of the described process. The view is in central vertical section, certain minor parts being shown in elevation.

In this showing, element 1 is a tubular reaction chamber of any convenient material, such as masonry or metal; this chamber having the form of a relatively short conduit of appropriate cross section. Usually I form it as a cylindrical or oval brick lined iron chamber. At one end, 2, material is forced into it by the action of any convenient stoking means. I have shown a cylinder 3 containing plunger 4 actuated by drive means 5 for charging. With the feed shown, the advancing column of material fills the entire cross section of the reaction chamber. Raw material enters through chute 6. At this end of the apparatus is drain 7, for condensed liquids, and outlet 8 leading to condensing and suction means (not shown) for removing vapors and gases. Ordinarily it is desirable to use scrubbing means (not shown) in connection with the condensing means where it is important, as it usually is, to remove light oils. Water or steam pipe 9 is provided in the event that cooling of the feed end by this means is desirable. However, with most coals there is sufficient moisture present or formed in combustion to provide all the cooling necessary. The material may be previously wetted down. Generally however this is not necessary; and sometimes, as with lignite, peat and wood, preliminary drying to a greater or less extent, is desirable. Within the reaction chamber the moving column of material may be regarded as passing through three zones A, B and C; A being the drying and preheating zone, B the carbonizing zone, while C is the high temperature zone. Hot carbonized material passing through zone C is discharged in a superheated condition at open end 10 in which it forms, as shown, an angle-of-repose face. Against this face is projected flame from element 11. This element 11 may be an air pipe or it may be a gas pipe with air induced through damper means 12. The materials coming from the end face of the column on the reaction chamber drop into chamber 13 forming a column or bed of hot fuel, the bed resting on grate means 14. Through this bed is forced in updraft, a gasifying draft current from pipe 15 which may be supplied with air, products of combustion or steam or mixtures of the same coming from pipes 16, 17 and 18. The particular character of draft current used depends on the material, and to some extent on the richness of gas want-

ed. Where the carbonized materials are coke or charcoal, that is, are rich in carbon, I generally employ liberal proportions of endothermics. Steam in addition to its endothermic action and its value in increasing the B. t. u. and quantity of the gas, has a shielding action on ammonia and in working with coke rich in nitrogen, where the production of ammonia is a desideratum, there may be enough water vapor introduced into the draft current to give a gas of the type of that formed in Mond producers. Gas produced with the aid of the draft current and not needed for passage through the reaction chamber goes to a place of storage or use (not shown) through outlet 19. It is usually mixed afterward with the gases from the reaction chamber where gas is wanted of higher B. t. u. than that of producer gas. Ash accumulation below the grate may be moistened by water from pipe 21; cooling the ash and furnishing water vapor for the draft current. The water introduced at 21 and vaporized in quenching the hot ashes may form a considerable proportion of the endothermic used. Ash is removed from the accumulation by star wheel 22 continuously or from time to time. Since the gasification chamber is supplied with hot carbon, the use of an endothermic in the draft current is particularly desirable as giving more gas and keeping the temperature of the fire-bed below the clinkering or sintering point. While other types of ash removal may be employed, the rotary grate shown is convenient and with the fire-bed temperature controlled by endothermics, as it should be, is practical.

The material treated in the present invention may be any vegetable material such as bark, wood, straw, sawdust, etc., from which it is desirable to obtain carbonization products and gas. In this event acid resistant metals or materials should be used at the cool end of the reaction chamber and in the condensing and gas collecting means. Or the material employed may be any bituminous coal, lignite, oil shale, or brown coal. The present invention is particularly useful in handling lignites of high water content since the heat of vaporization of water in the rear part of zone A is balanced out by condensation toward the feed end. The same considerations apply to peat.

I regard my invention as applicable in the dual treatment of any material capable of giving valuable products by low temperature carbonization and producer gas by high temperature gasification. I do not herein claim the apparatus illustrated, that forming matter in another and copending application Serial No. 31,148, filed May 18, 1925.

As shown, I have a single carbonization

chamber supplying the gasification chamber, but a plurality operating in parallel may be so used. In increasing capacity it is in general better to do it by increasing the size of the gasification chamber and increasing the number of carbonizing chambers feeding it; that a battery of reaction chambers, may be arranged in rows either side by side or one above another, to discharge into a single producer chamber, thereby furnishing a sufficient quantity of hot carbonized material to give any desired capacity for the producer. Because of the character of the material discharged by the carbonizing chamber operation of large size producer gas units is practicable. Ordinarily the flow of gases through the carbonizing chamber is induced, that is is produced by a suction device at some point, and proper valve arrangements at this point facilitate materially the establishment of the uniform and regulable carbonization I want. In using a plurality of carbonizing chambers feeding a single producer chamber, admission of air to the several carbonizing chambers is through a corresponding number of ports properly arranged for even distribution of flame and producer gas to each of the reaction chambers. However, with individual control of the suction in each chamber irregularities in this respect are not serious. Any desired disposition may be made of the producer gas which is not used in the carbonizing chamber to utilize its sensible heat and fuel value. Gas leaves the producer chamber in the present invention at a high temperature. Where such a place of use is a boiler plant, the distilling and gasifying plant may be made a part of the boiler setting.

What I claim is:—

1. In the low temperature distillation and carbonization and gasification of solid fuel containing volatile matter, the process which comprises establishing and maintaining a substantially horizontal moving column of material to be carbonized, impinging a flame of burning gases on one end of said column, passing said burning gases through the material in countercurrent, maintaining the opposite end relatively cool, whereby an intermediate stationary zone of carbonization is established and maintained at a self-regulating temperature, and gasifying the hot materials coming from the end against which the flame gases are directed by passing a draft current through the materials to effect such gasification.

2. In the distillation and carbonization and the gasification of solid fuel containing volatile matter, the process which comprises establishing and maintaining a relatively short horizontal moving column of pervious material with the feed end at a temperature below 212° F., directing against the other

end a flame of burning gas with a movement of flame gases through the column in countercurrent to the solid material therein, dropping hot carbonized material from the 5 flame-impinged discharge face into a vertical accumulation, gasifying said vertical accumulation by an updraft current passed therethrough and collecting gases coming from said moving column and from said 10 accumulation.

3. In the distillation and carbonization and gasification of solid fuel containing volatile matter with the formation of valuable byproducts, the process which comprises 15 carbonizing a substantially horizontal body of fuel by impingement on one end thereof of a flame of burning gases, simultaneously positively moving said body of fuel against the flame of burning gases, moving said 20 gases through the body of fuel in countercurrent, collecting vapors and gases at a point remote from the zone of impingement, and gasifying the hot carbon coming from the zone of impingement by means of a 25 draft current passing through the carbon.

4. In the distillation and carbonization and gasification of solid fuels containing volatile matter, the process which comprises establishing and maintaining a moving column of the material to be carbonized, maintaining the feed end at relatively low temperature and the discharge end at a high temperature with an intermediate zone where carbonizing conditions occur, temperatures at the hot end being maintained 30 by directing a flame of burning gases thereto, thereby setting up and maintaining a zone of pre-heat at the discharge end and also a zone of reduction where the flame 35 gases react with incandescent carbon and are changed from combustion gases to combustible gases, dropping the hot carbonized material from the flame impinged discharge face of the column into a vertical accumulation, 40 within a gasification chamber, gasifying the carbon residue by passing a suitable draft current and discharging the ash from the gasification chamber, and collecting and recovering the gaseous, volatile and liquid 45 by-products resulting in the carbonizing and 50 gasifying zone.

5. In the distillation and carbonization and gasification of solid fuels containing volatile matter, the process which comprises 55 establishing and maintaining a positively moving substantially horizontal column of

material to be carbonized, adding fresh material to one end, directing a flame of burning gases through the material from the opposite end in countercurrent, maintaining 60 the temperature and quantity of said gases sufficiently high to balance against radiation losses and the cooling action of the incoming material, thereby setting up and maintaining 65 a relatively stationary mid-zone of carbonization and distillation in the column, the temperature within the body decreasing from a maximum adjacent the point of entry of burning gases to a minimum adjacent the end at which fresh material is introduced, 70 with an intermediate mid-zone temperature depending on the reaction maintained in the mid-zone, dropping the hot carbonized material from the flame end of the column 75 into a gasification chamber, gasifying the 80 carbonized material by passing a draft current therethrough, using gases thus formed to maintain the flame and the zone of carbonization, discharging the ash from the 85 gasification chamber, and collecting and recovering the gaseous volatile-and liquid by-products formed in the carbonizing and 90 gasifying zones.

6. In the utilization of solid fuel containing volatile matter, the process which comprises establishing and maintaining a short, moving, substantially horizontal pervious column of fuel having a feed end at a relatively low temperature and a discharge end at a relatively higher temperature; said relatively higher temperature being substantially that of a flame of burning gases, with an intermediate carbonization zone between the feed end and the discharge end, the 95 temperature of the carbonization zone being determined by the heat evolved by the reactions therein and the temperature gradient from the discharge end to the feed end; supplying the discharge end with a draft of 100 flaming producer gas to maintain flame temperature thereon, conducting the flame gases through the column whereby a short producer zone is created near the discharge end, so discharging the hot material as to 105 form a bed and passing a draft current therethrough to form producer gas, hot producer gas therefrom being used to furnish said flame.

In testimony whereof, I have hereunto affixed my signature.

GEORGE W. WALLACE.
